UNITED STATES PATENT OFFICE.

GEORGE H. A. RUBY, OF EAST GRAND RAPIDS, MICHIGAN.

GYPSUM-BLOCK MACHINE.

Application filed October 31, 1927. Serial No. 229,803.

This invention relates to a gypsum block making machine, and is primarily concerned with a machine for making blocks from a gypsum or plaster of Paris cementitious composition continuously, whereby large quantity production of the blocks may be had.

Blocks of the character noted are of elongated rectangular parallelepiped form and have spaced openings made lengthwise there-
10 of to save material and lighten the blocks without material decrease of strength and, at the same time, provide air circulation openings whereby the blocks serve better as heat insulators and keep a building in which they
15 are used drier than would be the case with solid blocks.

My invention consists in many novel details and arrangements of parts for making a machine whereby quantity production of building blocks made of cementitious material is had, the blocks having spaced elongated openings therethrough; to provide mechanisms for drawing cores from the blocks, said cores being used in order to provide the elongated
20 openings therethrough and to also provide a means for drawing one end of each block form outwardly to leave a projecting end of the block free for engagement that the same may be grasped to take the block from the form when it has been completed and is sufficiently
25 set and hardened that it may be removed.

An understanding of the invention, the mechanism embodying the same and the objects and purposes thereof stated, as well as
30 many others not at this time specifically set forth, will be had from the following description taken in connection with the accompanying drawings, in which,

Fig. 1 is a plan view of one end of the block
35 making machine.

Fig. 2 is a plan view of the opposite end of
40 said machine.

Figs. 3 and 4 are side elevations of the
45 respective ends of the mechanism shown in plan
in Figs. 1 and 2.

Fig. 5 is an enlarged transverse vertical section through the machine substantially midway between its ends.

Fig. 6 is a fragmentary enlarged transverse
50 vertical section of the upper part of the
machine taken substantially on the plane of line
6-6 of Fig. 2.

Fig. 7 is a fragmentary side elevation with
55 parts broken away and shown in longitudinal
section substantially on the plane of line 7-7
of Fig. 2, and

Fig. 8 is a perspective view of one of the
gypsum blocks made in the machine.

Like reference characters refer to like parts
in the different figures of the drawings.

In the construction of the machine, a frame
is provided including a plurality of vertical
side posts 1 of angle iron. The posts at each
60 side of the machine are spaced apart and connected
to upper and lower horizontal tracks
2 also of angle iron, the horizontal flanges of
which extend inwardly. The sides of the
frame made up of the posts 1 and the angle
65 bars 2 are connected together and held in
proper spaced relation by cross angle bars 3
and 3^a fully shown in Figs. 3, 5 and 6.

A plurality of flat bars 4, one for each
block form in the machine, lie between the
70 track members 2. Each bar 4 at each end is
equipped with a roller carriage 5 to ride on the
inwardly extending horizontal flange of a
track 2. The flat bars 4 are connected in
proper spaced apart relation to a pair of con-
veyor chains 6 made up of pivotally
75 connected links and provided with rollers 7 at the
pivotal connections of said links. The chains
run around sprocket wheels 8, two of which
80 are located at each end of the machine, mounted
on horizontal shafts 9 which in turn are ro-
tatably carried in bearings 10 secured to verti-
cal posts 11 forming a part of the framework
85 of the machine and connected to the end posts
1 of the frame previously described.

One of the shafts 9, the one at the delivery
90 end of the machine is extended outwardly at one
end and is driven by an electric motor 12, suit-
able reduction gearing 13 being disposed be-
tween the motor and the shaft, whereby a con-
tinuous slow movement of the conveyor chains
95 6 takes place whenever the machine is in op-
eration. The bars 4 move continuously with
the chains over the horizontal flanges of the
upper tracks 2 and around the sprocket
wheels 8 at the delivery end of the machine
100 and back over the horizontal flanges of the
lower tracks 2 to the wheels 8 at the opposite
end of the machine.

Above each of the bars 4, toward one end
thereof, a number of spacing blocks 14 are lo-
cated and secured to which the bottoms 15 of
the block forms are connected. The parts 15
are of sheet metal and at one side each carries
a vertical partition plate 16 pivotally mounted
105 at its lower end as best shown in Fig. 7.
The plates 16 serve to divide the block forms
from those next adjacent. Each block form
has two ends 17 and 17^a the latter of which is

- permanently secured to the bar 4 over which it is located at one end of the bottom 15. The end 17 is provided at its lower edge with an inwardly turned flange 18 (see Fig. 6) which in one position, abuts against the other end of the bottom plate 15 with its upper side flush with the upper side of said bottom. Both the ends 17 and 17^a have openings 19 therethrough for the passage of cores which are designed to extend through the forms lengthwise thereof during the time that the cementitious material is being placed therein and while it is setting and hardening as it moves from the feeding end toward the delivery end of the machine.
- 15 The end 17^a is fixed and permanent with respect to the bottom 15 of the form with which it is associated. The end 17 is movably mounted upon a block 20 which in turn is slidably mounted on and over its associated bar 4, having spaced apart depending flanges 21, one extending downwardly at each side edge of the bar 4, with a plate 22 secured to and lying between said flanges 21 underneath the bar 4. This provides a slidable mounting for the block 20 and the attached end 17. The plate 18 associated with each block 20 at its end carries a depending roller 23, as shown, mounted to turn about a vertical axis.
- 20 At the opposite end of each form and beyond the permanent end member 17^a thereof, a second block 24 is slidably mounted above each of the bars 4. The block is equipped with downwardly extending flanges 21^a connected by a cross plate 22^a and each of the blocks 24 carries not only a lower roller 26 similar to the roller 23 previously described, but an upper roller 27 located directly over the roller 26. The blocks each carry a number of cores 25. In the drawing four of said cores are shown on each block 24 but in practice the number may be varied and will be equal to the number of elongated openings which are made through a block. The cores 25 extend inwardly from the inner end of each block 24, pass through the openings 19 in the end member 17^a, extend lengthwise of the form and are received in the openings 19 of the movable end member 17 of a form.
- 25 When the cores are withdrawn to the position shown in Fig. 6, the free ends thereof rest and are supported in the openings 19 in the relatively permanent end member 17^a of each form.
- 30 Inasmuch as the weight supported by each bar 4 is quite heavy the rollers 7 of the chains 6 are made to traverse tracks 28 attached to and supported by angle bars 29 which lie lengthwise of the upper part of the machine on the cross bars 3 of the frame located below the upper run of the conveyor, as shown in Fig. 5. In order to keep the bars 4 from bending or sagging down when they are at the lower run of the machine a bracket 30 is permanently secured to each bar 4 opposite

each form, carrying a roller 31 which rides on a flange or a Z-bar 32 located lengthwise of the machine and attached to other and lower cross bars 3 of the machine frame. This also is fully shown in Fig. 5.

70 The cementitious material is delivered from the machine from any delivery spout such as 33 in Fig. 3, of a cementitious mixture mixing apparatus entering the forms and being leveled and smoothed at the upper sides of the forms by the leveling apparatus indicated as a whole at 34. This leveling apparatus is no part of the present invention being fully covered by a previous patent granted to me. The feeding and leveling occurs adjacent one end of the machine which may be termed the feeding end of said machine. When the cementitious material is delivered to the forms the cores 25 are disposed in the forms between the ends 17 and 17^a thereof. The machine is approximately 90 feet in length and the feeding and leveling of the material takes place at approximately 10 feet from one end of the machine. The block forms move lengthwise of the machine toward its delivery end and carry the cementitious material therein which sets and hardens for between 50 to 60 feet or until the core pulling mechanism of the machine is reached. The feeding and leveling of the cementitious material and the way the blocks are in the forms during the time that the initial set of the material takes place is shown fully in Fig. 1.

85 As the upper run of the conveyor approaches the opposite or the delivery end of the machine, the rollers 26 and 27 on the core carrying blocks 24 come to a pair of cam bars 35 shown in Figs. 2 and 6 and ride against the outer sides of the vertical flanges thereof. It is evident that with the movement of the conveyor toward the delivery end of the machine, the cores are first broken loose and then drawn outwardly until the free ends of the cores rest in the openings in the fixed ends 17 of the block forms. When the cores have been substantially withdrawn the rollers 23 on the blocks 20 carrying the movable ends 17 of the block forms reach the shorter cam bar 36 carried on the cross bars 3 of the frame below the block forms and the movable end 17 will be moved outwardly a short distance or enough to move the flanges 18 beyond the ends of the blocks, leaving exposed undersides of the blocks at 37 (see Fig. 6) beyond the adjacent ends of the bottoms 15 of the forms. The blocks 38 in the forms have elongated openings 39 therethrough when the cores 25 have been withdrawn.

95 After the withdrawal of the cores and the movement of the movable end 17 of a block form has taken place, the cementitious material further sets due to the exposure of the material of the blocks around the openings 39 to the air. There is approximately 10 or 15 feet of the length of the machine during 100

which the blocks with the cores withdrawn take further set before the delivery of the blocks from the machine.

As the chains 6 start to pass around the 5 sprocket wheels 8 at the delivery end of the machine, the block forms separate and the vertical partition 16 tilts outwardly as shown in Fig. 7. The block may be grasped at one end at the exposed under side, indicated at 10 37, and withdrawn from the bottom plate 15 and thus taken from the machine.

The construction described is very practical 15 for the building of cementitious building blocks particularly where a gypsum or plaster of Paris cementitious composition is used. The drawing of the cores is accomplished in a simple and practical manner and it, of course, is to be understood that said cores and the 20 movable ends 17 are returned to operative position during the movement of the conveyor on its under-run before it reaches the sprocket wheels at the feeding end of the machine, and the cores are held in position against any 25 tendency to move outward by horizontal bars

40 shown in Figs. 1 and 2 against the inner sides of which the rollers 26 and 27 ride. Similarly, the rollers 23 ride against the inner edges of like bars 40 to hold the movable ends 17 in proper place with respect to the forms 30 during the time that the forms are receiving the material and said material is initially setting therein, or until the withdrawal cam bars 35 and 36 are reached.

The exposure of one end of a block at its 35 under side that it may be grasped by the hand to break the bond between a block and the bottom plate 15 of the form in which it is made is a very necessary feature of the invention. Otherwise it is very hard to remove the blocks 40 without breakage. Suction, as it is called, or actually the air pressure forcing the blocks against the bottoms of the form, is very heavy but the bond may be readily broken by a pull applied to the lower side of a block at one end 45 thereof; and this is permitted by reason of the construction of block form machine which I have made.

The invention is defined in the appended 50 claims and is to be considered comprehensive of all forms of structure coming within their scope.

I claim:

1. A consecutive series of block forms, each 55 comprising a bottom plate, a vertical side plate pivotally connected to the bottom plate, an end member permanently secured at one end of the bottom plate, a second end member located at the opposite end of the bottom plate and having an inturned flange, the upper side of which is flush with the upper side of the bottom plate, and means for mounting 60 said second end member for movement toward or away from said bottom plate.

2. A block form comprising, a bottom 65 plate, vertical sides, an end member perma-

nently secured at one end of the bottom plate, a second end member located at the other end of the bottom plate and having an inturned flange at its lower end, the upper side of which lies flush with the upper side of said 70 bottom plate, and means for movably mounting the second end member for movement toward or away from the bottom plate.

3. In a machine of the class described, an 75 endless conveyer, a plurality of bars located transversely of and connected to said conveyer, a bottom plate attached to and lying above each bar, a vertical side plate at one side edge of each bottom plate pivotally connected at its lower end to the bottom plate, an end member 80 permanently secured to each bar at one end of the bottom plate, a second end member located at the opposite end of the bottom plate and having an inturned flange, the upper side of which is flush with the upper side of said 85 bottom plate, and means for movably mounting the second end member on the bar whereby it may be moved toward or away from the adjacent end of said bottom plate.

4. In a machine of the class described an 90 elongated supporting frame, a horizontal shaft at each end of the frame, sprocket wheels on the shafts, endless conveyer chains running around said sprocket wheels, block forms carried by said conveyer chains, each including a bottom, a fixed end and a movable end mounted for movement toward or away from the adjacent end of said bottom plate, and means for moving said movable end of each block form outward automatically as the 95 conveyer, in the upper run thereof, approaches toward one end of the machine.

5. In a construction of the class described 100 a supporting frame, a horizontal shaft pivotally mounted at each end of the frame, 105 sprocket wheels on the shafts, a plurality of contiguous block forms carried by and located transversely of the conveyer chains, each form including a bottom plate, a vertical side pivotally connected at its lower end to said bottom plate, a fixed end secured at one end of said bottom plate, said end having a plurality of "openings" therethrough, a movable end located adjacent the opposite end of said bottom plate and likewise having a plurality of openings therethrough, means for mounting

110 said movable end for movement toward or away from the adjacent end of said bottom plate, a core carrying block movably mounted adjacent the fixed end of each block form, and a plurality of cores projecting from the inner end of the core carrying block to pass through the openings of the fixed end of each block form and into the openings of the movable end thereof, for the purposes described.

6. A construction containing the elements 115 in combination defined in claim 5, combined with means for automatically moving said core carrying block and the cores thereon associated with each block form outwardly as 120 125 130

the upper run of the conveyer approaches toward one end of the machine, and means for automatically moving the movable end of each block form outwardly when the cores 5 associated with said block form have been substantially withdrawn.

7. A block form comprising a horizontal bottom plate, vertical sides, a fixed end permanently secured at one end of the bottom 10 plate, a second end located at the other end of the bottom plate, having an inwardly projecting portion, the upper side of which lies in the same plane with the upper side of the bottom plate, and means for slidably mounting the movable end for movement toward or 15 away from the adjacent end of said bottom plate.

8. A continuous block making machine comprising, a continuous conveyer, a plurality of block forms located transversely of the conveyer, each having a bottom, a vertical side pivotally connected at its lower end to

the bottom at one side edge thereof, a fixed end and a second end slidably mounted for movement toward or away from the adjacent end of said bottom, said movable end having an inwardly extending flange, the upper side of which is flush with the upper side of said bottom, means for automatically moving said movable end of each block form outwardly at a predetermined point in the movement of said conveyer, and means lying lengthwise of the conveyer and underneath the upper run thereof for supporting the block forms and holding them against tendency to downward sagging.

9. A construction containing the elements in combination defined in claim 8, combined with additional means for supporting the block forms when the same are at the under run of the conveyer to hold them against tendency to sag downward.

In testimony whereof I affix my signature.

GEORGE H. A. RUBY.
